SPRAY GUN

Frank Frantisek Faktor, Hounslow, England

Application October 8, 1948, Serial No. 53,501

5 Claims. (Cl. 299—89)

1

This invention relates to spraying devices, and the like, and more particularly to a liquid sprayer or spray gun.

The main object of my invention is to equip a spray gun with facilities for readily interchanging either of a pair of nozzles capable of producing wide ranges of atomization from very fine mist to a sprinkling effect by the use of a wide range of air pressures.

Another object is to include means for changing the ratio between the atomizing pressure and the material feed pressure on the spraying fluid to be sprayed by the gun.

A further object is to provide means for effecting quick release of the operating lever or trigger mechanism to facilitate instantaneous dismantling of the same.

It is also an object to provide a spray gun of the indicated character with a removable unit including a nozzle, a gland and needle valve guide normally retained in position at the front of the gun by releasable means.

A practical object is, of course, to have a spray gun as indicated which is reasonably simple and rugged in construction and is not likely to get out of order.

Other objects and advantages of the invention will appear in greater detail as the specification proceeds.

In order to facilitate ready comprehension of this invention for a proper appreciation of the salient features thereof, the invention is illustrated on the accompanying drawings forming part hereof, and in which:

Figure 1 is a side elevation of a spray gun made according to the invention and embodying the same in a practical form, the view being partly in vertical section to disclose constructional details;

Figure 2 is a transverse section taken on line 2—2 in Figure 1;

Figure 3 is another section taken on line 3—3 in Figure 1;

Figure 4 is a plan view of the spray gun of Figure 1 with a portion in horizontal section to disclose internal details;

Figure 5 is a section of the forward portion of a modification of the gun;

Figure 6 is a side elevation of another modification of the gun, showing the spraying fluid container integral with and mounted above the latter.

Referring in detail to the drawings, and in particular to Figures 1 to 4 thereof, a spray gun, generally designated 7, comprises a gun casing 8

having three main portions formed integral, consisting of the gun barrel 9, the piston grip or handle 10, and the cap or cover 11. The cover portion 11 is threaded to receive the upper end or neck 12 of a container 13 adapted to contain a fluid to be sprayed, the neck 12 having threads 14 engaging the internally threaded portion 15 of the cap. Engaging the upper end of neck 12 of container 13 is a disk 16 of resilient material clamped between the upper part 17 of cap 11 and the upper end of container neck 12 to form a tight closure for the latter, the disk 16 having a central aperture 18 communicating with a passage 19 in the gun barrel 9 and opening into a large horizontal passage 20 therein which extends downwardly through the handle 10, as indicated at 21, the lower end of the hollow handle 10 being provided with an internally threaded opening 23 into which a nipple or connection (not shown) may be screwed for connecting the gun to an air pressure hose in order to supply the requisite air for propelling the fluid in container 13 out of the gun during spraying. Upon the back of the handle 10 is an upper finger stop 24 and below it is a locating projection 25, while on the front of the handle is a longer intermediate projection 26, the arrangement being such that when the hand is placed upon the handle 10 between the finger stops or locating projections 24 and 25, the second finger will engage beneath the intermediate stop 26 for a purpose which will presently appear.

Depending within the container 13 is an outlet tube or pipe 27 terminating at its lower end in a forwardly bent extremity 28 adjacent to the bottom 29 of the container, and having a threaded upper end 30 screwed into the lower end of a vertical bore 31 in the gun barrel 9, with a lock nut 32 on the end 30 engaging the underside of a metal disk 33 whereby the inner periphery of the resilient rubber or other material disk 16 is clamped against the top 17 of cap 11. In disk 33 is an aperture 34 through which the air from the hollow handle and passages 20, 19 passes down into the container in order to exert driving spraying pressure upon the fluid within the latter. Within the gun barrel 9 is screwed the threaded rear end 35 of a forwardly-directed nozzle 36 having a central bore 37 which is tapered at the forward end 38 to terminate in a small central aperture 39, while externally the forward end is also tapered at 40. The gun barrel 9 has a forwardly-directed hollow cylindrical portion 41 extending a short distance forwardly about the rear portion of the nozzle for a purpose

about to be described. The bore 37 within the nozzle 36 communicates with the vertical bore 31 in the gun barrel 9 so that the fluid within container 13, which is driven up by air pressure through tube 27 and into said bore 31, will be propelled through bore 37 toward the forward small aperture 39 and out through the latter. In order to govern the amount of fluid thus ejected from the spraying aperture 39, a long rod 42 forming a needle valve and of smaller diameter than bore 37 extends axially through the latter and at the forward end terminates in a tapered valve point 43 cooperating with the internal forward tapered portion 38 of bore 37 and aperture 39, so that rearward axial movement of rod 42 or needle valve will open communication between the bore 37 and spraying aperture 39 to a greater or lesser extent according to the distance needle valve 42 is moved rearwardly.

The needle valve 42 extends rearwardly across the bore 31 and slides through a hole in the vertical rear wall 44 in gun barrel 9 separating the bore 31 from the air passage 20. A washer or collar 45 is removably fixed on needle valve 42 by suitable means to engage the wall 44, while upon the rear portion of valve rod 42 within the passage 20 is circumscribed a coil spring 46 bearing against collar 45 at its forward end and bearing rearwardly against the forward end of a plug 47 screwed into the rear end 49 of the gun casing 8. The needle valve 42 extends slidably through the plug 47 and terminates at its rear end in a threaded extremity 48. Normally spring 46, by bearing against the collar 45 fixed on the needle valve rod 42, holds the tapered needle point or tip 43 thereof in closing relation to the aperture 39 in nozzle 36.

Threaded on the rear end 48 of the rod 42 is an adjustable stop nut 50 positioned to be engaged by an operating member hereinafter described, in a manner to move the needle valve rod 42 rearwardly and enable air and fluid from container 13 to be sprayed through aperture 39. The operating member comprises a transverse pin 51 extending through casing 8 above passage 20 and terminating at opposite sides of the casing in reduced ends, 52, upon which are pivoted the depending triggers 53 whose lower ends 54 are joined to form a yoke located above the forward handle projection 26 and bent slightly forwardly to accommodate the first finger when the second finger of the hand engages beneath the projection 26 on handle 10. A short distance below the pivot pin 51 the triggers 53 are pivoted at 56 to the forward ends of the legs 59, 59 of a U-shaped spring 60. The legs 59 are joined at their rear ends by a transverse yoke portion 62 normally resting upon the needle valve rod 42 rearwardly of the plug or nut 47 and immediately in front of the adjustable stop nut 50. The stop nut 50 is provided at the forward end thereof with a flange 63 against which the rear end or yoke 62 of the U-shaped spring 60 is adapted to engage when the triggers 53 are moved rearwardly about their pivotal mountings 52, while upon a portion of flange 63 of nut 50 an integral forward projection 64 overhangs the rear yoke portion 62 of the spring 60, in order to prevent the latter from being accidentally displaced from its position in front of flange 63 while resting on rod 42.

The arrangement is such that when the hand grips handle 10 with the palm located substantially between the locating projections 24 and 25 and the first finger engaging the front of the

triggers 53 and the other three fingers located upon the handle below the forward stop or projection 26, rearward movement of triggers 53 by the first finger will cause said triggers to swing upon their pivot mountings 52 and thereby move arms 59 of yoke member 60 rearwardly so that the transverse yoke portion 62 thereof will engage against flange 63 of adjustable stop nut 50 and thereby push needle valve rod 42 rearwardly and withdraw the forward tapered needle point 43 thereof from actual contact with the interior of spraying aperture 39 thereby allowing compressed air from the hollow handle 10 to pass through passages 19, 17 and 34 into container 13 to force the fluid in the latter up through tube 27 and into bore 31, and thence through bore 37 and out through orifice 39 past the tapered forward end 43 of the mentioned needle valve rod 42. Adjustment of the stop nut 50 determines and limits the rearward movement of the needle valve rod 42, against the resistance of the spring 46 when the triggers 53 are compressed toward the handle 10. As soon as the triggers 53 are released, spring 46 returns the needle valve rod forwardly to close the orifice 39. The plug 47 is fixed in position by means of a pin 65 extending downwardly through the rear end 49 of casing 8.

As thus far described, the apparatus serves to project a small stream of fluid from container 13 out through orifice 39 without, however, atomizing the same in the true sense. For this purpose the gun barrel 9 is provided with additional equipment surrounding the nozzle 36. The nozzle 36 is provided with a plurality of radially extending fins 66, best seen in Figure 2, defining air passages 67 therebetween, and upon the fins is slidably mounted a hollow nozzle 87 provided with a concave forward end 68 and an aperture 69 closely surrounding the conical exterior 40 of fluid-ejecting nozzle 36. Upon the rear portion of air nozzle 87 is a wide rim or flange 70 loosely surrounded by a retaining ring 71 having on its forward end an inwardly directed flange 72 engaging against the forward inclined shoulder 73 of the mentioned flange 70 to form a substantially air-tight connection at that point. The rear end 74 of the retaining ring 71 is reinforced in thickness and externally knurled and fits slidably upon the forwardly-projecting cylindrical end of gun barrel 9, and a retaining screw 75 extends through a diagonal slot 76 in the knurled end 74 of retaining ring 71 and is screwed into gun barrel portion 41, as best seen in Figure 4. When retaining ring 74 is rotated in a clockwise direction, that is, upwardly in Figure 4, the screw 75 being slightly loosened to allow free rotation, the lower portion of slot 76 engaging the screw will cause the retainer ring and the air nozzle 87 carried thereby to be shifted a short distance forwardly, thereby moving aperture 69 forwardly away from the conical tip 40 of fluid nozzle 36. Rotation of the ring 71 in the opposite direction brings the upper end of slot 76 into contact with screw 75 and moves the retaining ring 71 and its rear reinforced portion 74 rearwardly thereby causes the aperture 69 of the air nozzle 87 to be brought close to the tapered tip 40 of the fluid nozzle 36, thereby restricting the opening thereof and obviously allowing less air and fluid to issue between the orifice 39 and the tapered tip 40 of the fluid nozzle 36.

A pair of passages 79, 79 in the sides of the gun barrel 9 by-pass the vertical bore 31, from which the tube 27 projects downwardly into the

container 13, and connect the forward end of the air passage 20 with the rear end of chamber 78 in the forward end of the barrel 9, whereby compressed air is supplied to the passages 67. Within the chamber 78 is located a slidably movable washer 80 movable in the space between the forward end of the tubular cylindrical gun barrel portion 41 and the rear end of air nozzle 87. A relatively weak expanding spring 81 in chamber 78 is compressed between the washer 80 and the rear end of chamber 78 and normally acts to hold the washer 80 against the rear end 79 of the mentioned air nozzle 87 so as to close the rear ends of a pair of longitudinal passages 82, 83 formed in the nozzle 67, the forward ends of the passages 82 opening into the concave forward end 68 of the air nozzle at 83, 83. Normally, the air pressure present in chamber 78 tends to push the air nozzle 87 forwardly as far as the flange 72 of the retaining ring 71 will allow it to go, so that the engagement of this flange with shoulder 73 on the air nozzle will determine the position of the latter in the retaining ring. Due to the presence of the spaces 67 and the intermediate reduced portion 84 of inner nozzle 36, the air pressure exerts only a partial pressure on the rear of washer 80 tending to hold the washer 80 in closing relation to the passages 82 in the wall of air nozzle 87 in addition to the light pressure exerted by the spring 81, inasmuch as the air passes also through the opening of the washer 80 and around the reduced portion 84 of the inner nozzle 36.

Upon occasion it may be desired to use a substantially flat spray instead of the usual round or cone-shaped spray. On such occasion it is necessary to remove from the gun the washer 80, within retaining ring 71, in the rear of the air nozzle 87, so that the compressed air within chamber 78 will then enter through passages 82 and issue through forward orifices 83, 83, thereby exerting air pressure from above and below upon the mist atomized by the air from orifice 69 upon fluid issuing from orifice 39. The air nozzle 87 can be rotated to give the fan spray in any direction desired, other than the position shown.

In order to replace nozzle 36 by another of somewhat different character and capable of handling fluid of different viscosity, the screw 75 is merely unscrewed, and retaining ring 71 slid forwardly off the forwardly-projecting cylindrical portion 41 of gun barrel 9, the air nozzle 87 and washer 80 readily following the retaining ring in its removal so that nozzle 36 then projects in exposed condition from the cylindrical portion 41, fully accessible for unscrewing its rear end 79 from the gun barrel 9, and temporarily removing spring 81. The replacement nozzle is then screwed into place, after which the spring 81, washer 80 and air nozzle 87 are replaced, and finally the retaining ring 71. When sliding retaining ring 71 into position on the hollow cylindrical portion 41, the knurled rear portion 74 is adjusted to present the slot 76 in proper position on top. The screw 75 is then screwed down into the cylindrical portion 41 and the nozzle is fully assembled.

While the inner nozzle 36 has been described as having an inner threaded end 79 which is screwed into gun barrel 9, it is also possible to have a somewhat similar nozzle 86 provided, as shown in Figure 5, with a hollow cylindrical rear end 88 fitting into a central bore 89 of a gun barrel 90, the nozzle having a flange 91 form-

ing a stop to locate the rear end 88 in the bore 89. A knurled set screw 92 is screwed down through a threaded hole 93 in the gun barrel 90 with its lower end 94 engaged with the rear portion 88 of nozzle 86 to retain the latter in place. Unscrewing the set screw 92 a few turns will release the nozzle 86 so that it can be slid forwardly out of the gun barrel 90. In the upper portion 17 of the cap 11 is screwed the threaded upper end 30 of the pipe 27 to communicate with a bore 95 in the rear portion 88 of the nozzle 86, and with a longitudinal bore 96 of larger diameter than the needle valve 42 and extending therethrough. In the rear portion 88 of the nozzle 86 is screwed a gland plug 97 slidably surrounding the needle valve 42 and containing a gland packing 98 to prevent any of the fluid forced up through pipe 27 and bore 95 from escaping rearwardly into the air supply passage 99 of the spray gun, while allowing needle valve 42 to slide sufficiently to control by its forward conical end or tip 43 the small central orifice 100 of nozzle 86, in a manner already described in connection with the nozzle 36 of Figures 1 to 4.

Upon the nozzle 86 are provided fins 101, 101 similar to fins 66 of the nozzle 36, while the forwardly projecting hollow cylindrical portion 102 of the gun barrel 90 has the retaining ring 71 thereon with its air nozzle 87 and contains a spring 81 and a washer 80, previously described, the screw 75 being screwed down through the threaded hole 103, the device of Figure 5 being otherwise similar to the device of Figures 1 to 4. It should be obvious, however, that when the air nozzle and retaining ring are both mounted in position, as well as the mentioned screw 75, it is but necessary to remove said screw and release set screw 92 partially, when it will be possible to slide out both the inner nozzle 86, as well as the air nozzle 87, and also the retaining ring 71 for quick disassembly to facilitate cleaning of the parts. The gun barrel 90 has a bleeder passage 116 leading to the outside from the hole receiving rear end 88 of the inner nozzle 86 to allow any leakage tending to pass this nozzle to escape instead through passage 116.

Reverting now to the apparatus as shown in Figures 1 to 4, it may be mentioned that the trigger mechanism would, of course, be applied in exactly the same manner to the device of Figure 5 when complete, and this mechanism also lends itself to quick and easy dismantling. When it is desired to remove the needle valve 42 and otherwise dismantle either device, the device being disconnected from the air hose and free from any air pressure, the handle 10 is held in one hand and the other hand is used to move the nut 50 rearwardly a sufficient distance to allow the U-shaped spring 60 to be swung upwardly clear of the forwardly overhanging projection 64 of nut 50. When the spring 60 has been swung above the projection 64, one of the legs 59 is expanded laterally outwardly, as indicated in broken lines at 104 in Figure 4, so as to free it from pivot stud 56 upon which it was pivoted. In similar fashion, the other leg 59 is withdrawn outwardly, as indicated at 105, from the other pivot stud on that side, and the spring 60 removed. The triggers 53 can then be lifted off the pivot ends 52 and laid aside. Upon unscrewing cap 11 from the upper end 12 of container 13, access is provided to reach the washer 45 on the needle valve 42 through the passage 19 to withdraw the pin or other means used to hold the washer 45 rigidly on the needle valve rod, after

which the rod can be withdrawn rearwardly through the plug 47. Such complete dismantling of the gun may not be necessary, since only the nozzles, retaining ring 71, spring 81, and washer 80 are ordinarily removed for cleaning. Normally, even if the retaining ring and the nozzles are removed either as shown and described with respect to the form of the invention of Figures 1 to 4, or as shown in Figure 5, the triggers and U-shaped spring 60 may be removed, while the needle valve rod 42 remains assembled with the gun casing 8.

In the form of the invention shown in Figure 6, the fluid container is integral at 108 with the upper portion of the gun barrel 106. The hollow handle 109 is provided with a compressed air supply fed to its interior chamber 110 which communicates through a tube 111 in the upper portion thereof with the upper portion of the interior 112 of container 108. The chamber 112 within the container communicates with a downwardly-extending passage 113 communicating with the needle valve bore 114 within gun barrel 107. The upper end 114 of container 103 is closed by a screw cap 115, removal of which allows introduction of whatever fluid is intended to be sprayed from the gun. Otherwise the construction of the spray gun of Figure 6 is the same as those of Figures 1 to 4 or Figure 6.

Manifestly, other variations than those described may be resorted to and parts and features may be further modified or used without others within the scope of the appended claims.

Having now fully described my invention, I claim:

1. In a spray gun, a gun casing having an upward fluid passage therein, a tube connected to a source of supply of fluid to be sprayed and communicating with the upward fluid passage in the gun casing, and means communicating with a source of compressed air for applying air pressure to the fluid, a forwardly-directed hollow cylindrical gun portion projecting rigidly from the gun casing, the latter having a forwardly-directed opening within the hollow cylindrical gun portion communicating with said upward fluid passage, a fluid-ejecting nozzle detachably mounted in said opening and arranged to project forwardly out of said hollow cylindrical gun portion and having a longitudinally-disposed fluid passage communicating at the inner end thereof with said upward fluid passage, an externally and internally-tapered outer end on said nozzle having a small orifice communicating with the longitudinal fluid passage within the nozzle, a needle valve rod of smaller diameter than that of said longitudinal fluid passage extending through said nozzle and terminating in a tapered needle valve point with the internally-tapered outer end thereof, a spring in said gun casing biasing the needle valve rod with its tapered needle valve point into closing contact with said internally-tapered outer end, manually-operated means mounted upon said gun casing in effective position to move said needle valve rod longitudinally in opposition to said spring and thereby withdraw the tapered needle valve point of said needle valve rod from said internally-tapered outer end in said nozzle to allow ejection of fluid through the small orifice in the outer end thereof, a diametrically-enlarged portion on said nozzle within the outer end thereof having at least one passage extending longitudinally therein for passing compressed air from within said hollow cylindrical gun portion to the

externally-tapered end of said nozzle, said hollow cylindrical gun portion having at least one passage leading from the source of compressed air to the interior of said hollow cylindrical gun portion, means retaining said fluid-ejecting nozzle in place within the opening in the hollow cylindrical gun portion, a gland member mounted upon the needle valve rod and screwed into the inner end of the longitudinal passage in said fluid-ejecting nozzle, a tubular retaining ring rotatably mounted on the hollow cylindrical gun portion and extending beyond the forward end thereof, a hollow air nozzle slidably mounted on the diametrically-enlarged portion on the fluid-ejecting nozzle having a rear end extending rearwardly into the tubular retaining ring and formed at its forward end with an orifice surrounding the externally-tapered outer end of said fluid-ejecting nozzle, and means connecting said hollow air nozzle with the outer or forward end of said tubular retaining ring in such manner that upon partial rotation of the ring in either direction, the hollow air nozzle is longitudinally adjusted with reference to the fluid-ejecting nozzle and presents a greater or smaller opening between the externally-tapered outer end of the latter and the orifice in the outer end of said hollow air nozzle according to the direction in which said retaining ring is rotated.

2. In a spray gun comprising a hollow gun casting having a container for fluid to be sprayed detachably connected thereto, the features which include a gun portion integral upon the gun casting with a hollow cylindrical portion extending forwardly therefrom and having a downwardly-extending passage therein, a container cover integral with the gun casting, a pendently-disposed tube extending with its upper end into the downwardly-extending passage and adapted to extend with its lower end into the container for spraying fluid when the latter is connected to the container cover, a rear end portion upon said gun casting having a rear hole therein, a downwardly and rearwardly-extending hollow handle integral with the gun casting, the latter and the handle having an internal chamber opening through the lower end of said handle, the latter end of said handle being adapted to be connected to a source of compressed air, and the gun casting having a passage leading to the interior of the container cover from the internal chamber in said gun casting and handle, a forwardly-directed opening within said hollow cylindrical gun portion communicating with the downwardly-extending passage therein, a fluid-ejecting nozzle having one end detachably mounted in the forwardly-directed opening and extending forwardly from said hollow cylindrical gun portion, the nozzle having a longitudinal passage therethrough and terminating at the forward end in a restricted fluid-ejecting orifice, a wall in said gun casting separating the downward passage in the hollow cylindrical gun portion thereof from the internal chamber therein and having a hole aligned with the rear hole and the longitudinal passage in said nozzle, an axially-movable needle valve rod extending from within the latter longitudinal passage through the two holes and terminating rearwardly exteriorly of the rear end portion of said gun casting in an exposed operating end, a stop projection mounted upon the latter end, an air nozzle supported upon the forward end of said hollow cylindrical gun portion in effective position to atomize fluid ejected from said fluid-ejecting

nozzle, means for adjustably connecting the air nozzle with said hollow cylindrical gun portion, the latter having at least one passage by-passing said downwardly-extending passage therein and interconnecting the internal chamber within said gun casing and the interior of said hollow cylindrical gun portion independently of said fluid-ejecting nozzle, a needle valve point upon the forward end of the needle valve rod, a spring biasing the latter with its needle valve point forwardly into closing position with the restricted fluid-ejecting orifice in the fluid-ejecting nozzle, a pair of pivot members supported on the opposite sides of said gun casing, a pair of triggers having pivot apertures in one end of each fitting upon said pivot members and extending downward in spaced relation to said handle, a U-shaped spring having a rear yoke portion resting upon the rear exposed operating end of said needle valve rod within and forwardly of the stop projection thereon, and two substantially parallel arms projecting forwardly and individually terminating in forward ends upon the intermediate portions of said triggers, and a pair of pivot members pivotally connecting the forward ends of said two parallel arms of said U-shaped member with the intermediate portions of said triggers.

3. In a spray gun comprising a gun casing with a forwardly-projecting hollow cylindrical gun portion, and a rearwardly-disposed handle rigid with said gun casing, the features which include nozzle means supported upon the hollow cylindrical gun portion for ejecting atomized fluid therefrom, the handle and gun casing having an internal chamber opening through the end of the handle and the latter end being adapted to be connected to a source of compressed air, a hollow fluid container integral with said gun casing upon the upper portion thereof and having an upwardly-directed opening, a removable cover for closing the opening in the fluid container, the gun casing having a passage interconnecting the hollow interior of said fluid container and the interior of the hollow cylindrical gun portion to bring fluid to said nozzle means, the gun casing also having a second passage communicating with the internal chamber in the latter and said handle and extending to said hollow interior of said fluid container, an air tube fixed in the second passage and extending upwardly within said container and terminating below the opening thereof, a movable valve member controlling ejection of fluid from said nozzle means to the atmosphere, and manually-operated means mounted on said gun casing for operating said movable valve member at will.

4. A spray gun comprising a casing having a forwardly projecting tubular cylindrical barrel, a fluid spray nozzle mounted on said casing within and concentrically spaced from said barrel, said fluid nozzle having a forward end projecting forwardly beyond said barrel, said fluid nozzle being formed with an axial bore and terminating at its forward end in an internally and externally tapered tip forming an orifice communicating with and smaller in diameter than said bore, an air nozzle comprising a tube concentrically slidable on said fluid nozzle and extending beyond said tip, said tube having a wall at its forward end formed with a circular opening smaller in diameter than said tip and into which said tip projects in concentrically spaced relation to the edge of said opening, means for holding said air nozzle in longitudinally adjusted relation to said fluid nozzle, a needle valve

mounted on said casing and extending through said fluid nozzle bore in concentrically spaced relation thereto and having a tapered forward end positioned to cooperate with said orifice to determine the effective aperture of said orifice, means for supplying spray fluid under pressure to said orifice through said fluid nozzle bore, said needle valve being longitudinally movable in said fluid nozzle to selectively determine the effective aperture of said orifice, means for supplying air under pressure to the space between said nozzle and the interior of said tubular barrel, and operating means connected between said casing and said needle valve for moving said needle valve longitudinally in said fluid nozzle, said air nozzle being formed with spaced longitudinal air passages opening through the forward end thereof in positions to form a flat jet of spray emerging from said orifice, the rearward ends of said longitudinal air passages opening through the rear end of said air nozzle into the interior of said tubular barrel portion, and spring biased means within said tubular barrel portion normally closing the rearward ends of said longitudinal air passages.

5. A spray gun comprising a hollow casing terminating at its forward end in a cylindrical tubular barrel portion, a wall across the interior of said casing at the rearward end of said tubular barrel portion, a compressed air passage in said casing terminating at its forward end at said wall and having means for connection to a source of compressed air, a spray fluid container, means on said casing closing said container and mounting said container thereon, an air conduit in said casing leading from said air passage into the interior of said container whereby compressed air from said air passage is impinged upon spray fluid present in said container, said wall being formed with an internal chamber, a tube extending into said container and communicating with said chamber whereby fluid expelled from said container by compressed air enters said chamber under pressure, said chamber having a forwardly facing opening concentric with and opening into the interior of said tubular barrel portion, a forwardly projecting fluid nozzle having a rear end mounted in said chamber opening and a forward end reaching forwardly beyond said tubular barrel portion, said nozzle having a longitudinal bore communicating with the interior of said chamber and a reduced hollow conical forward end tapering to an interior diameter smaller than said bore and defining an orifice, a needle valve supported in concentrically spaced manner in said bore for axial movement therein, said needle valve terminating at its forward end in a tapered tip cooperating with said orifice, means for moving said needle valve forwardly and rearwardly in said bore to reduce and enlarge the effective area of said orifice, a tubular air nozzle concentrically and slidably mounted on said fluid nozzle and terminating at its forward end in a concavity and a wall behind said concavity formed with a circular opening concentrically spaced from said tapered forward end of said air nozzle and into which said tapered forward end projects, a ring slidably circumposed upon said tubular barrel portion and retainably engaging a portion of said tubular air nozzle, and releasable retaining means operating between said ring and said tubular barrel portion and holding said ring in a selected longitudinal position on said tubular barrel portion determining the degree of projec-

11

tion of said tapered forward end of said fluid nozzle in said circular opening of said air nozzle.
